UNITED STATES PATENT OFFICE.

CHARLES G. SCHAMU, OF LIVERPOOL, NEW YORK.

BEEHIVE.

1,100,847.

Specification of Letters Patent. Patented June 23, 1914.

Application filed October 16, 1912. Serial No. 726,047.

To all whom it may concern:

Be it known that I, CHARLES G. SCHAMU, of Liverpool, in the county of Onondaga and State of New York, have invented a 5 certain new and useful Beehive, of which the following is a specification.

This invention relates to beehives and particularly to the bases or bottom boards thereof, and it consists in the combinations 10 and constructions hereinafter set forth and claimed.

In describing this invention reference is had to the accompanying drawings in which like characters designate corresponding parts 15 in all the views.

Figure 1 is a front elevation of my beehive. Fig. 2 is a rear elevation of the bottom board. Fig. 3 is a plan of the bottom board, partly broken away. Fig. 4 is a sectional view on line "A—A," Fig. 3. Fig. 5 is a plan view of one of the detached partitions of the bottom board. Fig. 6 is an elevation of an adjustable gate of the bottom board. Fig. 7 is a fragmentary view 5 partly in section showing in side elevation, the right end of the bottom board looking upwardly in Fig. 3.

1 is the bottom board of the hive and 2 are the hive boxes mounted one above the other 30 on the bottom board. The bottom board 1 is here shown as formed with upper and lower chambers or compartments, the upper compartment or chamber being divided into front and rear chambers 3, 4 by an inclined 35 partition 5, and the lower compartment being divided into front and rear chambers 6, 7 by a vertical partition 8. The partitions 5 and 8 are arranged so that the upper rear chamber 4 is larger than the lower rear 40 chamber 7 and extends over the lower front chamber 6. The chamber 3 is in direct communication with the hive boxes through a suitable passage 3^a, Fig. 4, and is provided at its front end with an adjustable gate 9 45 comprising a roller of the same diameter as the height of the chamber 3 and provided with a plurality of cutouts 10, 11 and 12, of different depths, the cutout 12 being provided with a drone net, and the wires thereof 50 being spaced apart sufficient distance to permit the egress and entrance of the workers but to prevent egress of the queen and drones. The passage 11 is of sufficient width to permit the egress and entrance of the drones 55 and workers but not the queen and the passage 10 is of sufficient depth to permit all

classes of bees to have free entrance and egress. The roller is adjustable about its axis to bring the desired cutout in position and close the others and for this purpose is 60 provided with a handle 13, Figs. 3 and 7, located at one end thereof. The roller 9 is here shown as formed with trunnions 14, 15 at its opposite ends, the trunnion 14 extending into sockets formed on the inner 65 side face of one of the side walls of the bottom board or base, and the trunnion 15 extending entirely through an open ended slot 16 in the other side wall and carrying the handle or knob 13 at its outer end. The 70 open ended slot 16 permits the roller to be removed bodily. The gate 9 forms no part of this invention but constitutes the subject matter of my Patent No. 1,064,779, issued June 17, 1913. The chambers 4, 6 and 7 75 are also provided at their outer ends with suitable removable and adjustable closures 17, 18 and 19, Fig. 4, which are in the form of rollers, each roller having but one cutout in which is located a drone net. Said rollers 80 are adjustable into but two positions to entirely close the chambers or in position to open the chambers for the purpose of ventilation and for giving additional entrances for the workers. The rollers 17, 18 and 19 85 for the chambers 4, 6 and 7 are provided with drone nets of sufficient space between the wires to permit the workers to have free egress but not to permit the drones and queen to escape. These rollers are provided 90 with trunnions and handles similar to the trunnions 14 and 15 and handle 13 of the gate 9.

The chamber 7 is in open communication with the chamber 4, and the chamber 4 is 95 provided in its upper wall 20 with a plurality of openings as parallel slots 21 through which the bees can pass into and out of the hive box. For the purpose of preventing the bees from entering the chamber 7, the 100 chamber 4 is provided with a removable horizontal partition 22 which meets the inclined partition 4 at one end and engages with the roller 17 at its other end. This partition is in the form of a rectangular 105 frame slidable in suitable ways formed in the side walls of the bottom board or base and provided with a plurality of pivoted shutters 23 having a common operating rod 24. By removing the roller 17, the rod 24 110 can be operated to entirely close the shutters or open the same either for the pur-

pose of ventilation or for permitting the bees to have access to the chamber 7, or the partition 22 may be removed entirely for these purposes. The partition 22 also permits the ready removal of bees which die during the dormant season, the dead falling through the slots 21 of the wall 20 on the partition 22 and hence do not accumulate in the hive box. The location of this partition 22 beneath the top wall 20 is particularly advantageous in that the partition is out of the space in which the bees work or store honey and hence will not be sealed by the bees and made hard to remove. As will be understood by those skilled in the art, the top of the bottom boards is sealed and made tight by the bees.

The chambers 3 and 6 are connected by drone traps here shown as a plurality of truncated cones 25 depending from the wall 26 separating said chambers, each cone having a conical passage communicating with an opening 27 in the wall 26 and the walls of the passage and the periphery of the cone being smooth so that after a drone has passed through the cone into the chamber 6, he cannot return to the chamber 3.

In operation, all the gates or rollers may be turned to closed position, or the main gate 9 left in one of its open positions, or the roller 19 may be turned to a closed position and the shutters 23 closed, and the gate 17 turned to open position so that the hive will have a plurality of entrance and exit passages for the workers, or the gate 19 may be removed bodily and food placed in the chamber 7 at certain seasons of the year, and the gate again placed in position.

The gate 18 is primarily for the purpose of permitting the egress of workers in case any should find their way through the drone trap into the chamber 6, and is removable for permitting the removal of the drones.

When feeding the bees, the rollers 17, 18 and 19 are turned to closed position so as to reduce the number of "robber" entrances, and the main gate 9 opened or closed as desired, and the drone traps closed with plugs, as corks, so that the workers will not in their eagerness to get out of the hive, fall through the drone traps and perish.

This hive is particularly advantageous in that it can be readily and quickly adapted to all conditions and changes in bee life; and can be provided with ample egress and entrance openings for the workers without permitting the escape of the drones, and further, in that the drones can be readily removed and the gates can be adjusted so that the hive will have the proper amount of ventilation.

What I claim is:

1. A beehive having upper and lower chambers, a passage connecting the chambers, and a drone trap comprising a trun-

cated cone depending from the wall separating the chambers and having a conical passage alined with the former passage, the walls of the passage and the periphery of the cone being smooth, substantially as and for the purpose described.

2. A beehive having an entrance and exit opening for the bees, and a drone trap arranged near and in the rear of such opening, substantially as and for the purpose specified.

3. A beehive having an elongated entrance and exit opening for the bees, and a plurality of drone trap passages located near and in the rear of said openings, the passages having smooth conical walls, substantially as and for the purpose set forth.

4. A beehive comprising a bottom board having upper and lower chambers, the upper chamber being formed with an entrance and exit opening, and a passage connecting the chambers in the rear of said opening, and a drone trap comprising an inverted truncated cone depending from the wall separating the chambers, and having a conical passage alined with the former passage, the wall of the latter passage and the periphery of the cone being smooth, substantially as and for the purpose described.

5. A beehive comprising a bottom board having two chambers, one being formed with an entrance and exit opening constructed to permit egress and entrance of the workers and prevent egress of the drones and queen, and the other being also formed with an opening constructed to permit egress and entrance of the workers and prevent egress of the drones and queen, and a drone trap passage between said chambers, substantially as specified.

6. A bottom board for bee hives formed with a compartment and a transverse partition in the compartment, including a movable shutter operable for establishing and shutting off communication with the hive box, substantially as and for the purpose set forth.

7. A bottom board for bee hives formed with a compartment and a transverse partition in the compartment including a plurality of shutters movable into and out of position to coöperate with each other to entirely close communication with the hive box, or form a plurality of openings for establishing communication to the hive box, and means for operating the shutters, substantially as and for the purpose described.

8. A bottom board for beehives formed with a compartment, and a transverse partition including a frame and a movable shutter carried by the frame for establishing and shutting off communication to the hive box, substantially as and for the purpose set forth.

9. A bottom board for beehives formed

with a compartment, and a transverse partition including a frame having an opening, and a plurality of shutters movable into position to coöperate with each other and entirely close the opening or form a plurality of openings for shutting off and establishing communication to the hive boxes, substantially as and for the purpose described.

10. A bottom board for beehives formed with a compartment, and a transverse partition including a frame and a movable shutter carried by the frame, the partition being removable as a unit, substantially as and for the purpose specified.

15. 11. A bottom board for beehives, the bottom board being provided with a top wall having openings therethrough for the bees, and a horizontal slide below the top wall, substantially as and for the purpose set forth.

20. 12. A bottom board for beehives, the bottom board being formed with openings in its top wall and a slide located below said top wall and removable from the bottom board, substantially as and for the purpose described.

25. 13. A bottom board for beehives, the bottom board comprising upper and lower compartments, gates for the workers at opposite ends of the lower compartment, and at one end of the upper compartment, the gates being constructed to prevent egress of the drones and the queen, and a drone trap passage between the upper and lower compartments, substantially as and for the purpose specified.

30. 14. A bottom board for beehives comprising upper and lower compartments, a gate at one end of the upper compartment, the top wall of the upper compartment being formed with openings for the bees, and the lower compartment being in communication with the upper compartment, and a slide located below said top wall and being removable by a sliding movement upon the removal of the gate, substantially as and for the purpose set forth.

35. 15. A beehive comprising a base board having upper and lower compartments, each compartment being divided into front and rear chambers, the front and rear chambers of the upper compartment communicating with the interior of the hive boxes, a

drone trap passage interposed between the upper and lower front chambers, and the upper and lower rear chambers being in communication with each other, and gates for controlling the passage of bees and air, the gates being located at the outer ends of the chambers, substantially as and for the purpose described.

40. 16. A beehive comprising a base board having upper and lower compartments, each compartment being divided into front and rear chambers, the front and rear chambers of the upper compartment communicating with the interior of the hive boxes, a drone trap passage interposed between the upper and lower front chambers, and the upper and lower rear chambers being in communication with each other, adjustable gates controlling the passage of bees and air, the gates being located at the outer ends of the chambers, and means for closing communication between the lower rear chamber and the hive box through the upper rear chamber, substantially as and for the purpose specified.

45. 17. A beehive comprising a base board having upper and lower compartments, the upper compartment being divided into front and rear chambers, and the upper compartment having gates at its opposite ends, and the lower compartment also having gates at its opposite ends, the gate of the front upper compartment being adjustable to permit the egress and entrance of all classes of bees, or of the workers and drones only, or of the workers only, or may be adjusted to a closed position, and the other gates being adjustable to closed position or to position to permit egress and entrance of the workers only, and drone trap passages between the upper and lower compartments, substantially as and for the purpose set forth.

50. In testimony whereof, I have hereunto signed my name in the presence of two attesting witnesses, at Syracuse, in the county of Onondaga, and in the State of New York, this 11th day of October, 1912.

CHARLES G. SCHAMU.
